UNITED STATES PATENT OFFICE.

GUSTAV HAAS, OF FRANKFORT-ON-THE-MAIN, GERMANY, ASSIGNOR TO GENERAL ANILINE WORKS, INC., OF NEW YORK, N. Y., A CORPORATION OF DELAWARE.

APPARATUS FOR DELIVERING MEASURED DOSES OF POWDERED OR GRANULAR SUBSTANCES.

Application filed November 29, 1927, Serial No. 236,564, and in Germany December 1, 1926.

The present invention relates to an apparatus for delivering measured doses of powdered or granular substances particularly such of low mobility by means of a measuring chamber corresponding to the volume of the desired dose.

If substances of low mobility, as for instance coloring-matters, are to be dosed, the difficulty arises that the material to be dosed does not automatically glide into the space wherein it is to be dosed, but that it must be forced into this space by shaking and knocking which very often causes the formation of either clods or hollow spaces within the said space so that a satisfactory dosing is rendered impossible. For this reason substances of the said kind are in most cases dosed by weight, in spite of the fact that this method of dosing requires machines of a very complicated construction.

By the apparatus which constitutes the subject matter of my invention and the object of which is to obtain doses measured by volume, it is possible to dose even substances of low mobility.

The accompanying drawing illustrates one modification of an apparatus which has proved to be very suitable for delivering measured quantities of dyestuffs. Figures 1 to 4 show a vertical section of the apparatus as it appears in different stages of operation. Figure 5 shows a horizontal section on the line A—B of Figure 1.

The apparatus comprises a hopper *a*, the upper wider part of which is open, but which may be closed, if desired, and the lower narrower end of which is open. To this lower end of the hopper is directly attached the dosing chamber proper *b*, which is provided near its lower end with a sliding plate *f* or a similar device. In the center of the hopper *a*, containing the material to be dosed, is a guide channel formed by walls *c* which are fixed to opposite walls of the hopper *a*, as shown in Figure 5. In this guide channel are pistons *d*₁, *d*₂ and *d*₃, which are capable of up and down movement. The central piston *d*₁ is capable of moving independently of side pistons *d*₂ and *d*₃. Elastic blades *e*₁ are attached to the lower end of piston *d*₁ and elastic blades *e*₂ and *e*₃ are attached to the lower ends of pistons *d*₂ and *d*₃, respectively. These blades *e*₁, *e*₂ and *e*₃ are normally bent so that when

forced out of the guide channel they spring out into contact with the side walls of the dosing chamber *b*.

The two blades *e*₁ thus sever the material to be dosed while blades *e*₂ and *e*₃ serve to hold back the material in the hopper and relieve the blades *e*₁ of the weight of the said material. It is to be understood, however, that the blades *e*₂ and *e*₃ and attached pistons *d*₂ and *d*₃ are not absolutely necessary and may be omitted. By further forcing the piston *d*₁ downwards and simultaneously opening the lower slide-shutter *f* of the dosing-chamber, the separated material is forced out of the dosing-chamber. After the dosing chamber has been closed by the lower slide-shutter the piston *d*₁ is again drawn upwards, which causes the bent separating blades to return into the guide channel and to be again straightened therein, whereupon a fresh quantity of the material to be dosed can drop into the dosing-chamber. The movement of the pistons and the opening of the dosing-chamber can be effected either by hand or by mechanical means. The volumetric capacity of the apparatus may be adjusted in the known manner, for instance by displacing the walls of the dosing-chamber. The apparatus may also be provided with other devices commonly applied in dosing-apparatus, for instance with a storage chamber.

It is not necessary to fit the guide channel and pistons in the center of the hopper *a*; they can also be fitted laterally to the center but in such a manner that they run towards the dosing chamber in a vertical line. A worm-conveyor or a shovel may be mounted above the hopper for conveying the material to be dosed into the hopper, and they may serve at the same time to prevent the material from clogging. One of the sides of the dosing-chamber is made of glass plates *g* as shown in Figure 5 so that one can easily watch how the dosing proceeds and any formation of clods or hollow spaces in the dosing-chamber may be observed and redressed.

Figure 1 of the accompanying drawing shows the drawn up piston with the lower blades *e*₁, *e*₂, *e*₃. When the piston and blades are in this position, the material can drop from the hopper into the dosing chamber.

Figure 2 shows the blades when they have

left the guide channel c and are bent owing to their elastic property, the upper blades e_2 , e_3 serving to keep back the flowing material, while the blades e_1 serve to sever the measured dose. The slide-shutter f provided at the lower part of the dosing-chamber is already partly opened and allows the dosed material to drop into the receptacle.

Figure 3 shows the blades e_1 when they have reached their end position and the dosed material has been entirely forced into the receptacle to be filled, the slide-shutter f being entirely drawn out so as to open the chamber.

Figure 4 shows the slide-shutter f closing the chamber, all the blades having returned into the guide channel so that the material to be dosed can again drop into the dosing-chamber.

I claim:

1. An apparatus for delivering measured doses of powdered or granular substances comprising in combination a hopper, a dos-

ing chamber directly attached to the lower end of the hopper, a vertical guide channel fitted in the center of the hopper above the dosing chamber, a piston within the guide channel capable of up and down movement therein, said piston being provided at its lower end with two elastic blades so bent as to be capable when forced downward out of the guide channel of springing out in opposite directions horizontally across the width of the dosing chamber into contact with the walls thereof, and a suitable sliding plate at the lower end of the dosing chamber capable of opening and shutting the same.

2. An apparatus as claimed in claim 1 having three pistons side by side within the guide channel, the central piston being such as claimed in claim 1 and the two side pistons each having an elastic blade such as claimed in claim 1.

In testimony whereof, I affix my signature.

GUSTAV HAAS, Apotheker.
